UNITED STATES PATENT OFFICE.

MAURICE GANDY, OF LIVERPOOL, COUNTY OF LANCASTER, ENGLAND.

BELT WINDING AND STRETCHING MACHINE.

SPECIFICATION forming part of Letters Patent No. 269,520, dated December 26, 1882.

Application filed November 4, 1881. (No model.)

To all whom it may concern:

Be it known that I, MAURICE GANDY, a subject of the Queen of Great Britain, and a resident of the city of Liverpool, in the county of 5 Lancaster, in that part of the United Kingdom of Great Britain and Ireland called England, manufacturer of cotton belting, have invented certain new and useful Improvements in Winding under stretch Cotton-Canvas and 10 other Machine Belts and Apparatus therefor; and the following is a full, clear, and exact description of my invention in such full, clear, and exact terms as to enable any one skilled in the art to which it appertains or is most 15 nearly connected to make and use the same, reference being had to the sheets of drawings annexed to this specification, and to the figures of reference marked thereon.

My invention has for its object the nullifying or killing of the elasticity of machine-belts, especially cotton-canvas belts constructed of cloths stitched together, as patented to me in the United States of America on the 1st day of June, 1880, No. 228,186.

25 It is within my knowledge that belt-stretching machines of certain constructions are known in the United States of America. For example, I am aware that stretch-machines on the lever principle are in use for stretching the strips of 30 leather used in the manufacture of leather belts; and I am also aware that machines have been constructed to wind leather belts under a moderate stretch; but it is within my knowledge that such machines are incapable and inadequate 35 for so winding cotton-canvas belts or other belts as to nullify or kill the elasticity by the stretching process to which the belts are subjected.

In the drawings, Figure 1 is a sectional side 40 elevation illustrative of a machine used for winding belts under a slight tension, used solely for the purpose of winding the belt into a compact coil or parcel for sale. This machine is of known construction, and is only 45 here used by me to point out the state of the art prior to my present application for Letters Patent. In the drawings, B is the belt, which is led between the plate and roller a, and the rollers b b, the upper of which is carried on the 50 swinging arm b' and weighted by the weight b''. The belt B then passes between the roll-

ers c c and the spring-retained plates d d and the rollers e e. The belt is then wound on the barrel f, as illustrated, being kept in position during the winding by the roller h, which is 55 adjustable between two swinging arms, i, the guides being gaged on the roller h to suit the width of the belt being wound. By this machine the belt B is evenly coiled on the roller f, the slight tension of the mechanism insuring a compact coil.

Under my invention I so construct a winding-machine that I can, when winding, so coil belts that any elasticity that they may have is, so to speak, nullified or killed by winding 65 the belts on a barrel under stretch from the pressure of heavily-weighted nipper-plates. The belt remaining under this extreme stretch in the coil or parcel is, when opened and used, found to be free from elasticity, the same having 70 been, so to speak, nullified or killed.

The machine by which I accomplish the objects of my invention is illustrated in plan at Fig. 2. Fig. 3 is a sectional elevation through Z Z, Fig. 2. Fig. 4 is an end elevation of Fig. 75 2. Fig. 5 is a detail in section of the winding-barrel. Fig. 6 is an end view of the swinging bearing. Fig. 7 is an end view on a larger scale of the press-plates.

The machine consists of the expanding-barrel A, which is formed of the four segments encircling an inner barrel and driving-shaft, D. These segments are expanded by the cones E E E, which are operated by the shaft F and the screw-nut F', and bear against tapered 80 steps in the mid-feathers of the segments. This winding-barrel A has one bearing in the fixed and main frame H, which also carries the driving-gear. The other bearing of the barrel A is in a swinging bracket, J, provided with the 85 locking-collar K. (See Fig. 6.) The belt B is fed to the winding-barrel A through the gaged guide L and the press-plates M M', which are removable and interchangeable and sized to suit the different widths of the belt being operated upon, the plates gripping the belt equally over its entire width. The seat of the under press-plate, M, is rigid, and the upper press-plate, M', is operated by a hinged plate, M'', to 90 which the pressure-power is applied to any required extent by the lever N.

From the press-plates M M' the belt passes

under the roller P, which is provided with the adjustable guides Q Q, the adjustment being performed through the central screw-rod and hand-wheel, R.

5 The gaged guide, which is an essential feature of the machine, is detailed at Fig. 7, and consists of the gage-pieces L L', which travel on the bar S, and are adjustable by the right and left hand screwed rod T, worked by the wheel U.

By winding the belt on the expanding-roller A from the press-plates M M', which are subjected to an extreme nipping-pressure, I am enabled to wind the belts under such extreme tension that the belt is coiled under its maximum stretch, and the storing of the coiled belt under such maximum stretch kills the elasticity of the belt. To remove the belt from the barrel A, after it has been wound into the coil, I release the cones E, so that the segments close in and release the coil, which can be then withdrawn from the barrel A by opening the swinging bracket and bearing J, forming a gate.

15 25 Having now described my invention, I would have it understood that I disclaim the stretch-machine as shown at Fig. 1 of this specification; but

What I claim, and desire to secure by Letters Patent, is—

30 1. The method substantially herein described of winding and maintaining the belts under tension, which method consists of winding the belt directly from the tension-nippers or press-

plates, under maximum tension, upon an expanding-barrel for the purpose of nullifying or killing the elasticity, substantially as described.

2. A belt winding and stretching machine having an adjustable guide to gage the width of the belt, and the nipper-plates to hold the belt against the winding of the barrel, substantially as shown and described, for the purposes specified.

3. In a belt winding and stretching machine, 45 the interchangeable press or nipper plates made of separate pieces of steel or other suitable metal, and combined with the nipper-jaws and levers to hold and force the nippers together, substantially as described.

4. In a belt winding or stretching machine, the press or nipper plates constructed with the lower plate rigid and the upper plate hinged, and provided with pressure-power, substantially as herein described and shown.

5. In a belt winding and stretching machine, the winding-barrel made of segmental pieces, expanded and contracted by cones, substantially as shown and described.

6. In a belt winding and stretching machine, 60 the combination of a winding-barrel, A, with a fixed and swinging bearing, substantially as described, for the purpose specified.

MAURICE GANDY.
